TO AMERICAN SALES-BOOK COMPANY, LIMITED, OF TORONTO, ONTARIO, CANADA,
A CORPORATION OF ONTARIO, CANADA.

MANIFOLDING SALES-BOOK AND COVER THEREFOR.

1,184,716.

Specification of Letters Patent.

Patented May 30, 1916.

Application filed November 19, 1915. Serial No. 62,272.

To all whom it may concern:

Be it known that we, EDWARD K. BOTTLE and ADOLPH A. YERKES, citizens of the United States, residing at Elmira, in the 5 county of Chemung and State of New York, have invented certain new and useful Improvements in Manifolding Sales-Books and Covers Therefor, of which the following is a full, clear, and exact description, such as 10 will enable others skilled in the art to which it appertains to make and use the same.

Our present invention relates to manifolding salesbooks; it has particular reference to the triplicating books which are used in the 15 larger establishments, in which the original is sent to an auditor, the duplicate given to the purchaser, and a triplicate is made on another sheet, which is retained in the book until the latter is turned in for comparison.

20 It is highly desirable in such books to use a translucent sheet as the duplicate, and this we contemplate doing. We provide arrangements by which books of this class are more conveniently manipulated than in the past, 25 and also provide a place in which the triplicate sheets which have been used may be disposed and retained securely in position; so much so that even if the book be dropped they will not ordinarily fall out of place.

30 We also arrange the book in such a way that the pad of triplicates is disposed above the pad of originals and duplicates in such a way that the entries are made upon substantially a level surface. Such books are

35 usually provided with covers, and in our arrangement the cover is formed with a false back and a support, the latter having a double bend formed therein near one edge, this bend being permanently set in double

40 bent condition, as illustrated in the drawing; in the case illustrated the book is of the so-called "Paragon" form, in which the pads of sales-slips are bound at the ends, but it is obvious that other forms might be em-

45 ployed. The pad of original and duplicate slips is disposed upon the main or body portion of the support, while the pad of triplicates is secured at the end to that edge of the support which is raised above 50 the body or base thereof by means of the double bend. It will be observed that the double bend provides a pad-supporting sur-

face N raised above the main surface O of this support, these two surfaces being connected by an inclined surface portion P disposed at an obtuse angle to the surfaces N and O. The false back and the support are connected preferably at one end by some form of spring closure. We have shown a spring hinge, but other forms might be employed. The originals and duplicates, with a backing sheet therefor, are bound into a sheet at one end thereof; the triplicates are similarly bound into a stub opposite the first; and the backing sheets of both pads, 65 and an extension or retainer for holding them in place, are bound into one of the stubs, so that the book may be easily handled. The use and operation of the book will be detailed after the description. 70

The accompanying drawing shows in perspective one of our improved salesbooks.

Therein A is the support, which as shown at A¹ has a double bend at one end thereof; B is the false back connected to the support by means of the spring hinge B¹, which is secured by the eyelets b¹ b², and is provided with the coil springs b³ b⁴. These should be stiff, so that the parts A and B are pressed firmly together. It is obvious that a spring 80 closure without a hinge pin might be used; as this is a well known device, we have not deemed it necessary to illustrate it. C is an abutment against which the pad of triplicates bears, and secured upon it is a bail I, 85 holding the pad in place.

The pads are secured together, and are two in number, the one E of originals and duplicates, and the other H of triplicate sales-slips; D is the base of the pad E, 90 which is formed of manila or other reasonably stiff backing material. A part of this back is turned over to form a retainer D¹, which is passed under the bail I to hold the book in place against the abutment C in the 95 usual way. In practice this retainer is usually separate, and is attached when the stub is formed, but it is in effect a continuation of the base or backing D, and may be formed integral therewith if the material be tough 100 enough. A second backing-sheet D² is provided for the pad H, and this is of similar material.

The pad E is formed of opaque originals

F, and translucent duplicates G, formed integral with one another. Weakened lines pass across at the junction of the opaque and translucent materials, as at f, and the slips 5 are folded at this point; similar weakened lines are shown at f¹, where the address coupon is attached, and g, where the translucent duplicate is attached at one end to the others in the book so as to form a stub 10 E¹, the parts being secured in place by the staples e e in a well-known manner.

The pad of triplicates is formed of any desired material, usually of slips of the ordinary opaque paper, and the ends of these 15 are formed into a stub by staples e similar to those of the other stub. It will be observed that the backing-sheet D, and the backing-sheet D², as well as the extension or retainer D¹, are all connected in this stub 20 so that the books may be handled as integers; while to the free end of the backing-sheet D² is attached a double-faced carbon sheet K. The cover of the book may be formed either at the end or side as may be 25 desired, but in the present instance it is shown at L, attached to the side and broken away.

In operation, when an entry has been made upon the original F, it is duplicated 30 upon the translucent sheet G, being easily read through the latter, and it is triplicated upon the upper sheet of the pad H. After the entries are made, the slip G is removed at the weakened line g, and it may then be 35 separated from the slip F at the line f in the usual way. The next original slip is grasped, and drawn out from beneath the backing sheet d², drawing with it the next translucent duplicating slip; the two are 40 then laid upon the carbon sheet K, and the book is ready for a second operation. It will be observed that in this manipulation, it is not necessary for the salesman to handle the carbon sheet K at any time; and 45 this is a great advantage, inasmuch as it avoids soiling the hands, this being particularly desirable in stores where delicate goods are sold. The top sheet of the pad H may then be drawn up, which also may be effected 50 without handling the carbon; the false back B and the support A are then sprung apart, and the sheet from the pad H is passed between them. This, it will be observed, is readily effected by pressing the sheet down 55 with the finger into the opening between the double bend A¹ of the support A, and the false back B. After the sheet, as shown at H¹, is disposed in position the finger may be withdrawn at one side and the spring 60 hinge B¹ will press the false back and the pad support together, so that the sheets H¹ are retained in position.

We have found that the translucent sheet has great advantages in a book of this 65 description, inasmuch as the entry becomes

more and more distinct with time, as the coloring from the carbon sheet or other copying means penetrates into it more and more as it gets old. It also protects the filed sheet against alterations, as the coloring cannot be rubbed off the translucent slip without marring and injuring the latter. For these reasons, it is usually best with this salesbook to give the original entry to the customer and send the translucent sheets to 75 the auditor or other checker.

Obviously, changes of many kinds may be made in the embodiment of our invention without departing therefrom, and all such we aim to cover by the claims which we 80 append to this specification.

Having thus described our invention, what we claim as new and desire to secure by Letters Patent is:

1. In a triplicating salesbook, the combination of a support having a double bend therein near one edge providing a pad supporting surface raised relative to the main surface of the support, a pad of original and duplicate sales-slips, the originals of opaque, and the duplicates of translucent material, the pad having a stub located on the support at the edge opposite the double bend; with a pad of triplicate slips attached at their ends to form a stub, the stub located 95 upon the support adjacent to the double bend; and a double-faced carbon sheet between the duplicate and triplicate slips.

2. In a triplicating salesbook, the combination of a support having a double bend 100 therein near one edge providing a pad supporting surface raised relative to the main surface of the support, a pad of original and duplicate sales-slips, a second pad of triplicate sales-slips attached at one end to the 105 support adjacent to the double bend and lying partly on said raised surface, the first pad lying under said second pad, copying means between the sheets of the first pad and those of the triplicate pad, a false back 110 under the support, and a spring closure between the false back and the support.

3. In a triplicating salesbook, the combination of a support having a double bend 115 therein near one edge providing a pad supporting surface raised relative to the main surface of the support, a pad of original and duplicate sales-slips upon the support, a second pad of duplicating sales-slips attached to the support near the double bend and lying partly on said raised surface, copying means between the sheets of the first pad and the second, a false back adjacent to the support, and a spring hinge connecting the false back and the support, the false back and 120 support constituting a retaining means for the used slips of the triplicate pad.

4. As a new article of manufacture, a cover for a salesbook comprising a support having a permanently set double bend 125

therein near one edge, and means for retaining a pad located adjacent to such double bend.

5. As a new article of manufacture, a cover for a salesbook comprising a support having a double bend therein near one edge, a false back adjacent to the support, and a spring hinge connecting the support and the back.
10. 6. As a new article of manufacture, a cover for a salesbook, comprising a support, a false back, and a spring closure connecting the false back and the support.
7. In a triplicating salesbook, the combination of a support having a permanently set double bend near one edge, a pad of sales-slips, and a second pad of sales-slips, each pad having a backing-sheet; the first pad composed of original and duplicate slips attached to a backing sheet at the end away from the double bend, and the second pad attached to both the first and the second backing-sheets adjacent to the double bend in the support; with means for attaching the pads to the support; and copying means between them.
8. As a new article of manufacture, a triplicating sales-book comprising a backing-sheet, original and duplicate sales-slips attached at one end to the backing-sheet to form a stub; a second backing-sheet, triplicate sales-slips attached to the second backing-sheet at the end opposite the first stub to form a second stub, copying means attached at one end to the free end of the sec-
- ond backing-sheet, the first and second backing sheets being bound into the stub of the second pad.
9. As a new article of manufacture, a triplicate salesbook comprising a pad of 40 original and duplicate sales-slips formed integral and having weakened lines, the ends of the duplicates being attached to form a stub; a backing-sheet for the pad, one end of which is attached to the stub; 45 a second backing-sheet, triplicate sheets attached to the end of the second backing-sheet opposite the first stub to form a second stub; a double-faced carbon sheet attached to the free end of the second backing -sheet; a third sheet of relatively stiff material forming a retainer for the book, adapted to coöperate with attaching means upon a cover, the two backing-sheets, the retainer, and the slips of the triplicating 55 pad being bound together into a stub.
10. As a new article of manufacture, a cover for a salesbook comprising a support having a pad-supporting surface raised above the main surface thereof, said raised 60 surface connecting with the main surface by an inclined surface disposed at an obtuse angle to said raised and main surfaces.

In testimony whereof we affix our signatures in the presence of two witnesses.

therein near one edge, and means for retaining a pad located adjacent to such double bend.

5. As a new article of manufacture, a cover for a salesbook comprising a support having a double bend therein near one edge, a false back adjacent to the support, and a spring hinge connecting the support and the back.

10. 6. As a new article of manufacture, a cover for a salesbook, comprising a support, a false back, and a spring closure connecting the false back and the support.

7. In a triplicating salesbook, the combination of a support having a permanently set double bend near one edge, a pad of sales-slips, and a second pad of sales-slips, each pad having a backing-sheet; the first pad composed of original and duplicate slips attached to a backing sheet at the end away from the double bend, and the second pad attached to both the first and the second backing-sheets adjacent to the double bend in the support; with means for attaching the pads to the support; and copying means between them.

8. As a new article of manufacture, a triplicating sales-book comprising a backing-sheet, original and duplicate sales-slips attached at one end to the backing-sheet to form a stub; a second backing-sheet, triplicate sales-slips attached to the second backing-sheet at the end opposite the first stub to form a second stub, copying means attached at one end to the free end of the sec-

ond backing-sheet, the first and second backing sheets being bound into the stub of the second pad.

9. As a new article of manufacture, a triplicate salesbook comprising a pad of 40 original and duplicate sales-slips formed integral and having weakened lines, the ends of the duplicates being attached to form a stub; a backing-sheet for the pad, one end of which is attached to the stub; 45 a second backing-sheet, triplicate sheets attached to the end of the second backing-sheet opposite the first stub to form a second stub; a double-faced carbon sheet attached to the free end of the second backing-sheet; a third sheet of relatively stiff material, forming a retainer for the book, adapted to coöperate with attaching means upon a cover, the two backing-sheets, the retainer, and the slips of the triplicating 55 pad being bound together into a stub.

10. As a new article of manufacture, a cover for a salesbook comprising a support having a pad-supporting surface raised above the main surface thereof, said raised 60 surface connecting with the main surface by an inclined surface disposed at an obtuse angle to said raised and main surfaces.

In testimony whereof we affix our signatures in the presence of two witnesses.

Correction in Letters Patent No. 1,184,716.

It is hereby certified that in Letters Patent No. 1,184,716, granted May 30, 1916, upon the application of Edward Kirby Bottle and Adolph A. Yerkes, of Elmira, New York, for an improvement in "Manifolding Sales-Books and Covers Therefor," an error appears in the printed specification requiring correction as follows: Page 2, line 119, claim 3, for the word "duplicating" read *triplicating*; and that the said Letters Patent should be read with this correction therein that the same may conform to the record of the case in the Patent Office.

Signed and sealed this 18th day of July, A. D., 1916.

[SEAL.]
